UNITED STATES PATENT OFFICE.

JOHN R. WRIGHT, OF DETROIT, TEXAS.

LOCK.

Application filed March 31, 1923. Serial No. 629,027.

To all whom it may concern:

Be it known that I, JOHN R. WRIGHT, a citizen of the United States, residing at Detroit, in the county of Red River, in the 5 State of Texas, have invented certain new and useful Improvements in Locks, of which the following is a specification.

This invention relates to an improvement in padlocks and shackles therefor, the object being to provide a waterproof lock.

Locks of this type are usually placed on exterior doors and entrance of water into the lock casing naturally producing rust and gradually renders the lock useless.

15 The invention comprises the novel features hereinafter described, pointed out in the claim, and shown in the accompanying drawing in which:

Figure 1 is a side elevation of a lock, 20 the shackle being in open position.

Figure 2 is a sectional view, the shackle being closed.

Figure 3 is a section on the line 3-3 of Figure 1.

25 In the drawing 1 designates the lock casing and 2 the locking mechanism, of any desired type and not forming a part of the present invention. The key opening 1^a is in the bottom of the lock so that rain will not drive into the interior therethrough. The shackle 3 is of the conventional type, modified as hereinafter pointed out. I have illustrated a rotating type of shackle and

on the top of the casing 1 is an annular flange 4 which receives the free end of the shackle 35 when in closed or locked position.

Surrounding the upper end of the shackle opening 2^a in the top of the casing 1 is an annular flange or tubular portion 5. Snugly fitting over and around this flange 5 is a 40 beveled elastic washer 5^a preferably formed of rubber, but any elastic waterproof composition having durable wearing qualities will do. An overhanging, undercut flange 45 or shield 6, conical in form, is carried by or formed on the end of the shackle that enters the lock opening, and just far enough from the tip end portion to permit easy locking of the shackle. This overhanging portion fits over and compresses the washer 50 or gasket 5^a, forming a perfectly tight waterproof joint and effectually closing the lock at this point against entrance of moisture.

What I claim is:—

A padlock, comprising a body portion having an outwardly extending tubular portion integral therewith, a beveled gasket mounted on the tubular portion, and a shackle slidably mounted within the tubular portion and provided with an enlarged conical shield having an undercut annular groove adapted to snugly engage said gasket when the shackle is in its locked position.

In testimony whereof I affix my signature.

JOHN R. WRIGHT.
